CLAIM

I claim the ornamental design for a pet hair remover, as shown and described.

DESCRIPTION

FIG. 1 is a top, front and right side perspective view of a pet hair remover showing my new design;

FIG. 2 is a bottom, front and left side perspective view thereof;

FIG. 3 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an enlarged view of the portion labeled "9" in FIG. 1;

FIG. 10 is an enlarged view of the portion labeled "10" in FIG. 2;

FIG. 11 is an enlarged view of the portion labeled "11" in FIG. 2; and,

FIG. 12 is an enlarged view of the portion labeled "12" in FIG. 2.

The dot-dash broken line rectangle frames define the boundary of an enlarged view and form no part of the claimed design.
